UNITED STATES PATENT OFFICE.

MARTIN ZAWISTOWSKI, OF BROOKLYN, NEW YORK.

LOCK.

1,417,963.

Specification of Letters Patent. Patented May 30, 1922.

Application filed May 5, 1920. Serial No. 378,969.

To all whom it may concern:

Be it known that I, MARTIN ZAWISTOWSKI, a citizen of the United States, and resident of Brooklyn, in the county of Kings and State of New York, have invented certain new and useful Improvements in Locks, of which the following is a specification.

This invention relates to locks for drawers, doors, lids or other closures or movable members and involves certain novel features of construction and arrangement of the bolt, tumbler and bolt operating mechanism.

In my improved lock the bolt is mounted to turn about an axis and is so formed that when rotated to operative position, it holds the locked members not only against normal relative movement but also against all other relative movements.

As one important feature of my lock, the bolt is in the form of a flanged disk with one side cut away along a chord so that the chord may approximately coincide with the side of the lock casing when the bolt is in non-locking position, or the bolt may be rotated through 180°, more or less, and the flanged portion brought outside of the casing and into locking engagement with the receiver or retainer. As another feature, I provide an operating member which is so geared to the bolt that it may be turned through one complete rotation to turn the bolt through one-half a complete rotation, in other words, from non-locking to full locking position or vice versa. As another important feature, I provide a novel form of tumbler which will positively lock the bolt in either of two opposite positions and prevent rotation thereof, the bolt operating mechanism being so designed as to actuate both the tumbler and the gearing.

My improved lock in its preferred form involves a very small number of parts of simple, inexpensive and rugged construction, easily assembled and held against any possible accidental displacement. The arrangement whereby the operating member makes a complete revolution for one-half revolution of the bolt, readily adapts the device for use with a removable operating key, as the key may be withdrawn with the bolt in either of two positions.

In the accompanying drawings:

Figure 1 is a face view of the operating mechanism viewed substantially on the line 1—1 of Figure 4;

55

Figure 2 is a view of the opposite side of the mechanism and taken on the line 2—2 of Figure 4;

Figure 3 is an end view of the casing viewed from the left hand end of Figure 1;

60

Figure 4 is a central longitudinal section;

Figure 5 is a detail of the operating mechanism; and

Figure 6 is an elevation partly in section showing a key controlled operating mechanism.

The specific bolt illustrated includes a metal disk 10 presenting a cylindrical flange 11 on one face thereof at the periphery. The member forms only the major segment of a circle, a minor segment being omitted or cut away along a chord of the circle forming an approximately straight edge 12 on the disk. The disk is mounted to rotate about a suitable pivot or journal member which may be rigid with the disk and rotatable in its bearings or rigid in the bearings and having the disk rotated thereon. The disk or lock bolt is preferably mounted in a suitable casing; one end wall 14 of which has a slot 15 corresponding in size and shape to the contour of the disk along the flat surface or edge 12 of the latter. With the bolt in the position shown in Figure 1, the straight edge 12 of the bolt may substantially coincide with the end wall 14 of the casing and said straight side may lie within and substantially close the slot 15. By rotating the disk through 180° the straight side may come entirely within the casing, as shown in Figure 2, and the flanged segment of the disk will project beyond the end wall 14 of the casing.

In connection with the lock, any suitable retainer may be employed which will engage with the flanged disk and prevent separation or any other relative movements of the lock casing and bolt retainer. I have shown a form of retainer in Figure 6 which includes a casing 16 with a slot in the edge thereof corresponding to and opposed to the slot 15 of the bolt casing. The retainer has an upstanding projection 17 around which the flange 11 may pass during the rotation of

the bolt. This projection may be of such form that it cooperates with the wall of the casing and leaves merely a narrow groove or passage for the flange 11. As the flange 5 passes around this projection, it positively prevents any separation of the bolt retainer and the bolt casing either in a direction at right angles to the plane of the disk or in said plane. Furthermore, due to the length 10 of the slot 15 and the fact that the disk extends across from its casing to the retainer along the full length of this slot, any twisting or turning movement of the retainer and bolt casing is prevented.

15 Rigidly secured to the disk or formed integral therewith is a gear wheel 18. To economize space this is preferably on the same side of the disk as the flange 11. Meshing with the gear is a pinion 19 of one-half 20 the pitch diameter. The diameters of the gear and pinion are such that the pinion may lie closely adjacent to the surface of the disk and between the periphery of the gear and the inner surface of the flange 11.

25 Due to the fact that the pinion is of one-half the pitch diameter of the gear, a complete rotation of the pinion will effect a one-half rotation of the locking bolt and a complete rotation of the pinion will move the 30 lock the required distance between full locking and non-locking positions.

The face of the disk opposite to the gear is provided with a central raised portion 20 presenting a pair of diametrically opposed 35 radially facing recesses 21. The diameter along which these two recesses are located is at right angles to the chord along which the edge 12 lies. These recesses serve to receive my improved tumbler and retain the bolt disk in either of its two main positions. The tumbler is in the form of a sheet metal 40 plate 22 lying between the body of the disk and the wall of the casing and presenting a locking lug 23 which may enter either of the recesses 21 or ride along the periphery of the raised portion or boss 20. Means are provided for resiliently pressing this tumbler member into operative position and for normally holding it in such position. In the 45 form shown such resilient means include a pair of coil springs 24 disposed between the end wall of the casing and an up-turned flange 25 along one edge of the tumbler plate 22. For holding the springs in position, this flange may have lugs 26 struck out therefrom and extending endwise into the springs. The plate may be of a width 50 substantially equal to the width of the interior of the casing so that the plate can move only in a single direction. The flange 25 may extend to the opposite side of the casing as shown in Figure 4 and a portion of the plate may lie between the disk bolt and the wall of the casing so as to guide that 55 portion of the plate. The plate may be of

approximately the same thickness as the height of the boss 20, as is shown in Figure 4. As the springs are mounted adjacent to the opposite ends of the plate and the locking lug or tooth 23 is midway between the opposite ends, the lug will be pressed directly toward the axis of the bolt disk. As the plate is guided by the opposite edges of the casing, it cannot turn under the influence of any lateral pressure on the lug 70 23. Preferably the opposite side edges of the lug are parallel as are also the opposite side edges of each recess 21 so that any strain on the bolt disk, tending to rotate it, cannot act to force the lug out of the recess. 75 Preferably the extremity of the lug, as well as the entrance portion of each recess, is beveled or inclined so that the lug will be more easily guided into the recess when the locking bolt approaches each of its two normal positions.

For forcing the tumbler plate back against the springs 24 and thereby withdrawing the lug 23 from the recess 21 to permit rotation of the locking bolt, I provide an operating mechanism associated with the pinion 19. This member is shown as having a collar portion 27 with a major portion of its periphery cylindrical. At one side there is a recess in the form of a flattened portion or reentrant angle 28 with which a flange 29 engages. This flange is shown as being formed of a tongue struck out from the central portion of the tumbler plate 22 and bent around the edge of the bolt disk 10, as is shown particularly in Figures 1 and 4. The end portion of this tongue is normally pressed toward the collar 27 and rides on the surface of the latter as the member is turned. The tongue may have a flat end if the recess 28 on the collar 27 is merely a cut away segment or it may be slightly pointed as shown in Figure 1 in case the recess is in the form of a reentrant angle. As the collar 27 is rotated, it acts as 105 a cam on the end of the tongue 29 and thereby forces the tumbler plate 22 backward from the position shown in Figure 1 and until the lug 23 is withdrawn from the recess 21. The form of the co-acting parts 110 on the collar 27 and the tongue 29 are such that the range of movement of the tumbler plate 22 is properly proportioned to the co-operating engagement of the lug 23 and recess 21.

As the locking bolt cannot rotate until the lug 23 is withdrawn from the recess 21 and as the pinion 19 can only rotate by or with the locking bolt, I provide lost motion connections between the member 30 which carries the collar 27 and the pinion 19 which is coaxial with the collar. As shown particularly in Figure 5, the member 30 has a pair of oppositely disposed outwardly extending flanges or ears 31 disposed in recesses 32 in 115 120 125 130

the pinion, although materially narrower than said recesses. The width of the recesses 32 in respect to flanges 31 is dependent upon the angular movement of the collar 27 which is necessary to force back the tumbler plate. The flanges 31 are shown in Figure 5 as intermediate of the opposite sides of their respective recesses which is the normal position when the bolt disk is locked by lug 23 and the tongue 29 enters the recess of the collar 27. By rotating the member 30 with its collar 27 and projections 31 in either direction, the first effort will be for the collar to force back the tongue 29 and tumbler plate and release the bolt. By the time the bolt is released the projections 31 will reach the end of the recesses and further rotation of the operating member 30 will turn the pinion and bolt disk. When the pinion has been rotated through a complete revolution, the bolt disk will have been rotated through one-half a revolution and between complete release and complete locking positions. It will, of course, be evident that the recesses may be so positioned that the operating member may turn in only one direction from normal and, in that event, the end of the tongue 29 and cam collar 27 might be so formed as to prevent rotation of said collar in other than this same direction.

I do not wish to be limited to any particular means for turning the operating member. In Figure 4 I have illustrated merely a conventional form of handle 33 connected to the operating member 30. In case it is desired to rotate the operating member by a removable key, I may provide a common form of mechanism in which the key 34 enters a slot in a barrel 35 which latter may be directly connected to the operating member 30 in any suitable manner. The barrel 35 and its casing 36 may have co-operating tumblers or any other suitable means whereby the barrel cannot be rotated except when the proper key is inserted. I have not illustrated the details of such a barrel and casing construction as such is old and common in the art and forms no portion of my present invention.

I do not wish to be limited to any specific form of casing or method of mounting my improved lock. Merely for purposes of illustration I have shown a preferred casing which includes a sheet metal box with a separable wall 37. This wall may be secured to the surface of the door or other member to be locked in any suitable manner, as for instance by screws 38 shown in dotted lines in Figure 6. One edge of this wall 37 may have lugs or tongues 39 which may project through corresponding apertures in the end wall 40 of the casing opposite to the end wall 14 which has a slot 15. The end wall 14 is shown as having an extension or flange 41 which may lay along the edge of the door

or other closure member and be secured thereto by screws 42, shown in dotted lines in Figure 6. The wall member 37 may first be secured in place and then the balance of the casing attached by first catching the tongues or lugs 39 into their registering apertures and then swinging the casing into final position. When the screws 42 are inserted and the door closed no screws or other fastening means will be exposed at either side of the door and, therefore, there will be no parts exposed which can be removed for detaching the lock in the construction as shown in Figure 6. When a key is employed the barrel 36 is shown as being secured directly to that wall 37 of the lock casing by screw bolts 43. The opposite parallel walls of the casing may be held in proper spaced relationship not only by the edges of the casing but also by spacers 44 which may be rigidly secured to either of the two opposite walls. In some cases these spacers may be rigidly secured to one wall and screws may extend through the other wall into central apertures in the spacers 44 for holding the opposite walls together. These spacers are shown at opposite sides of the tumbler operating tongue 29 and the plate 22 is shown as having recesses through which the spacers extend and of such size that the spacers do not interfere with the free movement of the tumbler plate.

Having thus described my invention what I claim as new and desire to secure by Letters Patent is:

1. A rotatable bolt for locks, comprising a disk forming the major segment of a circle and presenting a cylindrical flange along the curved portion of its periphery, a gear rigid with said disk on one face thereof and a boss rigid therewith on the opposite face and having tumbler engaging portions at diametrically opposite points.

2. A lock, including a rotatable locking disk, a sheet metal plate adapted to engage with said disk to lock the latter against rotation, a rotatable member for sliding said plate to inoperative position and driving connections between said rotatable member and said disk.

3. A lock, including a rotatable locking disk having diametrically opposed recesses, a slideable sheet metal plate having a projection adapted to engage with either of said recesses to lock the disk against rotation, a rotatable member for sliding said plate to inoperative position and driving connections between said rotatable member and said disk and having limited lost motion.

4. A lock, including a rotatable bolt member having a pair of diametrically opposed recesses, a slideable plate having a lug adapted to enter either of said recesses and lock said bolt against rotation, a rotatable member having cam engagement with said plate for

withdrawing the latter and releasing said bolt and means for rotating said bolt when released.

5. A lock, including a rotatable bolt member having a pair of diametrically opposed recesses, a slideable plate having a lug adapted to enter either of said recesses and lock said bolt against rotation, a rotatable member having cam engagement with said plate for withdrawing the latter and releasing said bolt and means for rotating said bolt when released, said last mentioned means having lost motion connections with said rotatable member.
- 15 6. A lock, including a locking disk forming the major segment of a circle and presenting a flange along the curved portion of the periphery, a gear rigid with said disk, a pinion meshing with said gear, a tumbler 20 plate adapted to engage with said disk for holding the latter against rotation, a tongue formed integral with said plate and extending transversely across the periphery of said disk to the opposite surface thereof and a

rotatable member having a cam surface for 25 engaging with said tongue to move said plate to inoperative position and having lost motion connections with said pinion.

7. A lock including a rotatable bolt comprising a disk forming the major segment of 30 the circle and presenting a cylindrical flange along the curved portion of the periphery, a gear rigid with said disk on the face thereof bearing said flange and a boss rigid therewith on the opposite face and having tumbler 35 engaging portions, a slideable tumbler and a pair of coaxial members having lost motion connections, one of said members serving to operate said tumbler and the other of said members comprising a pinion 40 engaging with said gear and disposed between the periphery of the latter and the inner surface of said flange.

Signed at New York city in the county of New York and State of New York this 28th 45 day of March A. D. 1920.

MARTIN ZAWISTOWSKI.
